[57] CLAIM

The ornamental design for a mirror housing, as shown.

DESCRIPTION

FIG. 1 is a perspective view of a mirror housing showing my new design;

FIG. 2 is a front elevational view thereof;

FIG. 3 is a first edge elevational view thereof;

FIG. 4 is a rear elevational view thereof;

FIG. 5 is a second edge view thereof, as seen from the side opposite that of FIG. 3;

FIG. 6 is a first side elevational view thereof;

FIG. 7 is a second side elevational view thereof, as seen from the side opposite that of FIG. 6; and,

FIG. 8 is a front elevational view of a mirror housing showing a second embodiment of my new design.

The opposite side view of the first and second embodiments, FIGS. 2 and 8, that are not shown in the drawings, are plan and unornamented and form no part of the claimed design.
